UNITED STATES PATENT OFFICE.

JOHN FLETCHER FORD, OF HAWTHORNE, CALIFORNIA.

ROTARY PUMP.

1,318,319.

Specification of Letters Patent.

Patented Oct. 7, 1919.

Application filed March 23, 1916. Serial No. 86,082.

To all whom it may concern:

Be it known that I, JOHN FLETCHER FORD, a citizen of the United States, residing at Hawthorne, in the county of Los Angeles 5 and State of California, have invented certain new and useful Improvements in Rotary Pumps, of which the following is a specification.

This invention relates to improvements in 10 rotary pumps and has particular relation to pumps employing rotary pistons and generally having eccentric members for actuating the said rollers and the mechanism is especially adaptable to the pumping of 15 water from wells of various depths.

It is an object of the invention to provide 20 a rotary pump in which an eccentric member is moved for actuating a roller piston mounted in the pump casing, the structure being such that one piston or a plurality 25 may be employed according to the work desired to have the pump accomplish.

It is also an object of the invention to provide 30 a rotary pump having a piston chamber for receiving one or more rotary pumps, and having a partition for forming an inlet chamber and a discharge chamber outside the piston chambers, a suitable valve mechanism being provided for controlling the directions of the liquids passing through 35 the pump.

It is a further object of the invention to provide 40 an eccentrically operated roller piston pump in which the piston is so arranged that it rolls around in the pump thus eliminating much friction that would otherwise be developed and making it possible to construct the pump in a simple manner.

It is a still further object of the invention 45 to provide a pump with one or more rollers adapted to move about upon the inner periphery of the pump's walls to propel liquids through the pump, eccentric members being also provided for propelling the 50 said pistons, the invention also including a gravity actuated valve adapted to engage the peripheries of the pistons to direct the liquids operated upon by the said pistons. With these and other objects in view the invention comprises certain novel constructions, combinations and arrangements of parts as will be hereinafter more fully described and claimed.

In the accompanying drawing forming a 55 part of this specification:

Figure 1 is a vertical cross sectional view taken through a pump constructed in accordance with this invention, and showing one of the pistons and valves in side elevation.

Fig. 2 is a vertical sectional view taken upon the line 2—2 of Fig. 1.

In the said drawing a preferred form of the mechanism forming the subject matter 65 of this invention has been disclosed, and the details and features of the invention will now be more specifically set forth, reference being had to said illustration.

In the said drawing 5 indicates a pump 70 cylinder, the ends of which are closed by end walls 6, the lower portions of which are mounted upon suitable standards 7. While the pump may use only one piston, it is usually preferable to employ two or 75 more pistons, and the drawing sets forth a pump in which two pistons are used, the pump cylinder being divided by a vertical partition 8 for this purpose. A shaft 9 extends through the pump cylinder and finds 80 bearings at 10 in the walls 6 thereof, packing or stuffing boxes 11 being also provided to prevent leakage at said bearings. Within the walls 6 and between them and the central circular partition 8, eccentrics 12 and 85 13 are fitted, and fastened upon the shaft 9 usually by means of keys 14 so that the rotation of the said shaft will cause a rotation of the eccentrics also. In a two piston pump the eccentrics are set diametrically opposite each other as clearly shown in Fig. 1 of the drawing. Mounted upon the eccentrics 12 and 13 are roller pistons 15 and 16, the said pistons having a central bearing 90 closely fitting upon the peripheries of their eccentrics, while each piston is made of a suitable thickness outside the eccentrics so that it will just fit between the highest point of its eccentric and the inner surface of the cylinder 5. It will be readily understood by reference to Fig. 1 of the drawing that as the eccentrics turn with the shaft, the pistons are rolled upon the inner surface of the cylinder walls always filling the space opposite the longest radius of the eccentric entirely around the path of its movement. A reference to Fig. 1 will also show that a space is left at other points between the pe-

ipheries of the pistons of the cylinder walls to receive and propel liquids that may be passed through the pump.

At the top of the pump the wall of the cylinder is interrupted at 17 for a sufficient space to afford a discharge outlet and an inlet opening or port. An angular shaped partition 18 is also mounted upon the cylinder walls, adjacent to said ports and an auxiliary pump casing 19 is arranged to inclose the said partition and also to leave an ample space outside the same to accommodate a valve 20 which directs the movement of the liquids propelled by the pump. The 10 said partition 18 forms within it an inlet chamber 21, while between the said partition and the walls of the auxiliary casing 19, an outlet or exhaust chamber 22 is afforded, within which chamber the valve 20 is movable. Connecting with the auxiliary casing 19 and entering one end thereof, is an inlet pipe 23, the said pipe opening into the space 21 within the angular partition 18. At the other end of the auxiliary 20 casing 19 is an outlet or discharge pipe 24 which communicates with the space within the said casing 19 and between it and the angular partition 18.

The valve 20 is the same for both pistons 30 and is pivoted at 25 in the auxiliary casing 19 and has a curved arm portion 26 adapted to fit the outer curved surface of the partition 18. A shoe carrying portion 27 fits the other curved portion of the partition 35 18, the surface of which has a radial curvature with the pivot point of the valve as a center. The portion 27 forms a gate which carries a pivoted shoe 28 at its lower edge adapted to fit upon the periphery of the 40 roller piston beneath. The valves with their gate and arm portions are made alike and are made of a proper length to fit and move between the end walls 6 of the pump cylinder and the partition 18, as indicated 45 in Fig. 2 of the drawing. The arm portions 26 of the valves are somewhat cut away on their opposite edges as at 29 to permit the movement of liquids from beneath the said arm when they are lowered, for the trapping 50 of liquids between the valves and the angular partition 18, would prevent a proper operation of said valves. While the valves are only made the width of the pistons it will be noted by reference to Fig. 2 that the angular partition 18 extends the full length of 55 the pump.

In operation, the shaft 9 is rotated by any suitable power, not shown, and the eccentrics 12 and 13 turn with the said shaft and 60 cause the roller pistons 15 and 16 to roll upon their entire peripheries around within the cylinder of the pump. As the pistons roll in the direction of the indicating arrows, liquid is drawn into the intake chamber 21 65 through the pipe 23 and also into the piston

chamber below. As the pistons roll farther the liquid is forced around in the pump casing and thence it is forced into the discharge chamber 22. The valve shoes 28 are kept constantly in contact with the peripheries of the roller pistons, the gate portions 27 moving upwardly and downwardly in contact with the adjacent portion of the angular partition 18. The said valves with their shoes thus prevent the water or other liquids from moving in the wrong directions and insure the forcing of the liquids around in the cylinder from the intake to the discharge portion of the mechanism. While any desired arrangement of the pistons with respect to each other may be had, they are usually opposite each other as indicated in Fig. 1 of the drawing, so that when the piston 15 is discharging a maximum quantity of liquid in the discharge chamber 22, the other piston 16 is drawing in a maximum supply of liquid into the inlet chamber 21 and into its portion of the cylinder. In this way the discharge pipe 24 is caused to deliver a continuous stream of liquid from the 90 pump.

The arrangement of the gravity gate valves is such it will be noted, that the weight thereof and the weight of the water in the auxiliary casing 19, together with the 95 hydraulic pressure of the liquid in said chamber 22 causes each valve to be held downwardly whereby the shoes 28 will at all times be held in positive contact with the peripheries of the roller pistons.

The structure of the pump secures a desired advantage in the fact that the wear will be evenly distributed upon the peripheries of the pistons, and the friction of the contacting parts will not be appreciable, 105 thus adding to the durability and the high efficiency of the pump. Of course it will be understood that the minor details of the device may be considerably varied and mechanical equivalents may be substituted all 110 within the spirit and scope of the invention.

What is claimed is:

1. In a rotary pump, a cylindrical casing having an opening in the periphery thereof, a valve casing attached thereto and forming 115 a cover for said opening, said valve casing having inlet and outlet chambers therein and a partition separating said chambers, one wall of said partition extending into and dividing said opening into inlet and outlet ports, a rotor eccentrically mounted in said pump casing and adapted to contact with the inner periphery thereof, and a valve pivotally supported in said valve casing and adapted to constantly engage the periphery 120 of said rotor, as set forth.

2. In a rotary pump, a main casing having a cylindrical body, an eccentric rotor mounted therein and adapted to contact 125 with the inner surface of said casing, a valve 130

casing attached to the outer periphery of said main casing and having an inlet chamber and an outlet chamber therein, an opening being formed in said main casing and having communication with said inlet and outlet chambers, a partition in said valve casing having an upwardly curved portion and a downwardly curved portion, closing communication between said inlet and outlet chambers, said downwardly curved portion terminating at a point on the line of movement of said rotor, and a valve in said valve casing for engagement with said rotor.
